UNITED STATES PATENT OFFICE.

ANTONIO LLODRA OBRADOR, OF MANILA, PHILIPPINE ISLANDS.

CONTINUOUS DISTILLING APPARATUS.

1,106,832.

Specification of Letters Patent.

Patented Aug. 11, 1914.

Application filed August 31, 1911, Serial No. 647,054. Renewed April 29, 1914. Serial No. 835,333.

To all whom it may concern:

Be it known that I, ANTONIO LLODRA OBRADOR, subject of the King of Spain, residing at Manila, Philippine Islands, have 5 invented certain new and useful Improvements in Continuous Distilling Apparatus, of which the following is a specification.

This invention relates to improvements in continuous distilling apparatus of the type 10 wherein the mash and the vapors pass through the various instrumentalities in opposite directions, the operation proceeding on the counter current principle, and wherein in the vapors from the boilers pass through 15 a main distilling column in which condensates are recovered and returned to the boilers.

The primary feature of the present improvements is the provision of an auxiliary 20 column which is arranged adjacent to the main column above referred to and is in communication with the latter and with the boilers. The mash instead of passing directly into the main column or into the boilers 25 passes into the auxiliary column, and from the latter to the boilers. By virtue of these features of construction and operation, a number of important advantages are obtained, viz., the mash which passes into the 30 auxiliary column is raised to a temperature but slightly less than that of the boiler with which said column is in communication, this being effected by waste heat from said boiler, whereby the more volatile constituents of the 35 mash are vaporized and pass directly to the main column, thus preliminarily diverting a considerable portion of alcohol from the boilers so that the heavier parts only of the mash with their accompanying oils and acids 40 pass into the boilers and are therein more readily vaporized; the auxiliary column raises the mash to a temperature which it is not possible to secure with any ordinary fore-warmer; and, the solid matters contained 45 in the mash do not pass into the main column and consequently the necessity of dismantling this column every few months for the purposes of cleaning is avoided.

A further feature of improvement is the 50 provision of a collecting chamber and a collecting plate of special construction at the upper end of the main column to receive oils and other heavy condensates which may be drawn off in a special receptacle, and are 55 thus prevented from flowing back through the column and into the boilers.

The invention is illustrated in the accompanying drawings wherein:

Figure 1 is a diagram, partly in section, of the improved apparatus. Fig. 2 is a 60 vertical sectional view showing the main and auxiliary columns and the boilers. Fig. 3 is a similar view showing a condenser which is employed at a certain stage of the passage of the mash and the vapors. Fig. 4 is a detail 65 sectional view of the improved ebullioscope.

Similar characters of reference designate corresponding parts throughout the several views.

The mash may be supplied from any suitable reservoir, as for instance, the large elevated vat 1 from which leads a pipe 2, the flow of mash through the pipe 2 being controlled by a suitable regulating valve 3. The pipe 2 communicates with the lower end of a 70 refrigerating tower 4 and the mash after rising through the tower, passes by way of a connecting pipe 5 to an analyzing cylinder 6, passing from the latter through a pipe 7 to the auxiliary column 8. A supplemental 75 valve controlled connection 9 is provided between the cylinder 6 and the pipe 7 for use in case the level of the liquid in the cylinder 6 is not as high as the opening of the pipe 7.

The auxiliary column 8 may be of any approved construction and, as shown, is generally similar to the main column 10 with which it communicates by a pipe 11. The pipe 11 leads from the uppermost of the superposed chambers of the auxiliary column 80 to a suitable chamber of the main column. The auxiliary column also communicates with a boiler 12 by one or more pipes 13 which depend into said boiler. The boiler 12 forms the last of a series and may be arranged above an intermediate boiler 14, which receives the mash from the boiler 12 through a valve controlled pipe 15. The mash passes from the boiler 14 through a pipe 16 to a boiler 17 which is the first of the 100 series and which is subject to direct heat, as shown. The boiler 17 is provided with a discharge pipe 18 for the spent mash and in which is interposed the improved ebullioscope attachment 19, to be hereafter specifically described. The pipes 13, 15, and 16, as well as the pipe which returns condensates from the column 10 to the boiler 12, are provided at their discharge ends with traps of any suitable construction, which serve to 105 prevent the passage of vapors through said pipes.

The vapors from the boiler 17 pass by way of the pipe 20 to the boiler 14, and from the latter by way of the pipe 21 to the boiler 12. From the boiler 12 the vapors pass to the columns 8 and 10, the vapors passing through the column 8 partially combining with the more volatile portions of the incoming mash and passing through the pipe 11 to the column 10. From the column 10 the vapors pass by a pipe 22 to a worm 23, which is arranged in the cylinder 6 and wherein the heavier vaporous constituents are progressively condensed and returned by pipes 24, of which a desired number may be employed, to the main column 10, the condensates descending through the successive chambers of said column and being ultimately returned to the boiler 12. For the purpose of thus returning the condensates to said boiler, the lower chamber of the column 10 communicates in the usual manner with the boiler 12 by means of a pipe 10^a having its end within said boiler provided with the usual trap to prevent the passage of vapors through said pipe. Each pipe 24 is fitted, near its point of connection with the cylinder 6, with a valve 24^a whereby the amount of condensate which is returned to the column 10 may be regulated as desired in accordance with the quantity and grade of alcohol which it is desired to recover. Obviously, if the valves 24^a are positioned to reduce the quantity of condensate returned to the column 10, the amount of alcohol recovered will be proportionately greater, although the alcohol will be of somewhat lower grade. The ends of the pipes 24 which project into the column 10 are down-turned so that their points of discharge will be submerged in the liquid in said column in order to prevent vapors from entering said pipes. From the worm 23 the vapors pass by a pipe 25, to condenser 26, which may be of any desired form. As shown, said condenser includes a series of tubes through which water, admitted by a pipe 27 and led off by a pipe 28, circulates. The vapors are cooled in the condenser 26 and leaving the latter pass, by a pipe 29, to a worm 30, which is arranged in the tower 4. The worm 30 discharges the high proof alcohol into a suitable receiving tank 31.

The column 10 in addition to the usual superposed chambers in which the various grades of condensates are recovered, has at its upper end a supplemental chamber 32, which is afforded by the provision of a collecting plate 33. The latter is formed with a comparatively large number of perforations and the perforations are circumscribed by upwardly projecting flanges 34, which afford upon the upper side of the plate 33 a number of intercommunicating canals or passages, upon which oils or other base matters not previously recovered and

which would otherwise pass into the worm 23, are condensed, the condensate being discharged by a pipe 35, into a suitable vessel 36.

The ebullioscope 19, to which a general reference has been made, is arranged at the upper ends of the two legs of the pipe 18 and includes an elongated somewhat ogee bulb 37, which connects said legs and which is fitted with a suitable air vent 38 and a drain cock 39. The bulb 37 is also fitted near its discharge end with a suitably packed perforated copper tube 40, which incloses and protects the bulb of an L-shaped thermometer 41. The vertical leg of the thermometer projects beyond the bulb 37, and its horizontal leg is associated with a suitably supported plate 42, which carries a sliding scale 43. When the operation of the apparatus is started, the cock 39 is opened to prevent the heated liquid from gaining access to the bulb of the thermometer. When the boiling point is reached, which indication is had by the mercury becoming steady in the leg of the thermometer, the cock 39 is closed. The boiling point first attained is that of water and is taken as the zero of the scale 43, the latter being moved to bring its zero indication in line with said boiling point. When alcohol commences to pass with the spent mash this condition, as well as the percentage of alcohol passing, is indicated by the fall of the mercury in the leg of the thermometer and thereupon the intake and outflow of mash is stopped by operating the valve in the pipe 15, until all the alcohol remaining in the boilers is recovered.

Aside from the advantages heretofore set forth, the construction has the further advantages of providing for a continuous operation and of the recovery of high proof alcohol, and is capable of completely extracting the alcoholic contents from the mash, providing that the latter does not exceed 12% alcoholic strength.

Having fully described my invention, I claim:

1. In a continuous distilling apparatus the combination with a main distilling column and a series of boilers connected together and ultimately passing their vapors to the main column of an auxiliary distilling column arranged adjacent the main column and in communication with the 115 boilers to receive vapors therefrom and also in communication with the main column to pass vapors thereto, and a mash conducting pipe communicating with the auxiliary column to deliver mash thereto, the said auxiliary column passing the mash delivered thereto by the said pipe to the boilers.

2. In a continuous distilling apparatus, the combination with a main distilling column and a series of boilers connected to- 130

gether and ultimately passing their vapors to the main column of an auxiliary distilling column arranged adjacent the main column and communicating at its lower end 5 with the boilers to receive vapors therefrom, the auxiliary column embodying a plurality of superposed communicating chambers through which the vapors pass and in which condensates are recovered and returned to 10 the boiler, a connection between the uppermost of said chambers and the main column to pass vapors to the latter, and a mash conducting pipe communicating with the auxiliary column to deliver mash thereto the 15 said auxiliary column passing the mash delivered thereto to the boilers.

3. In a distilling apparatus, a series of boilers and a distilling column through which the vapors delivered by the boilers

pass, the column embodying a plurality of 20 superposed chambers in which condensates are recovered and having at its upper end a supplemental chamber, the base of which consists of a plate having a comparatively large number of perforations and having 25 upwardly projecting flanges, circumscribing the perforations and defining a multitude of communicating canals, and a pipe connected to the plate whereby the oils and other base matters collecting thereon may 30 be drawn off.

In testimony whereof I have hereunto set my hand in presence of two subscribing witnesses.

ANTONIO LLODRA OBRADOR.
